US0D1033096S

(12) United States Design Patent (10) Patent No.: US D1,033,096 S
(45) Date of Patent:  Jul. 2, 2024

(54) 2-TIER-PULL-OUT ORGANIZERS

(71) Applicant: Shenzhen Chenglai Technology Co., Ltd., Shenzhen (CN)

(72) Inventor: Yun Liao, Shenzhen (CN)

(73) Assignee: Shenzhen Chenglai Technology Co., Ltd., Shenzhen (CN)

() Term: 15 Years

(21) Appl. No.: 29/861,270

(22) Filed: Nov. 29, 2022

(51) LOC (14) Cl. 06-06

(52) U.S. Cl.

USPC D6/675.2

(58) Field of Classification Search

USPC D6/672, 675-675.1, 675.2, 682-682.1,
